(57) **CLAIM**

The ornamental design for a cordless pulling tool, as shown and described.

DESCRIPTION

FIG. 1 is a front perspective view of a cordless pulling tool;

FIG. 2 is a front view thereof;

FIG. 3 is a right side view thereof;

FIG. 4 is a left side view thereof;

FIG. 5 is a top view thereof;

FIG. 6 is a bottom view thereof; and,

FIG. 7 is a back view thereof.

The phantom lines in FIGS. 1 through 7 are for illustrative purposes only and do not form part of the claimed design.
